ELECTRICALLY OPERATED LAVATORY DRIER

Original Filed Nov. 29, 1927

FIG. 1.

FIG. 2.

INVENTOR:

GEORGE A. BURGESS,

By Robert Burns,

ATTY.

UNITED STATES PATENT OFFICE.

GEORGE A. BURGESS, OF WAUKEGAN, ILLINOIS, ASSIGNOR TO CHICAGO HARDWARE FOUNDRY COMPANY, OF NORTH CHICAGO, ILLINOIS, A CORPORATION OF ILLINOIS.

ELECTRICALLY-OPERATED LAVATORY DRIER.

Original application filed November 29, 1927, Serial No. 236,490. Divided and this application filed May 7, 1928. Serial No. 275,718.

This application is a division of application, Serial No. 236,490, filed Nov. 29, 1927.

This invention relates to that type of lavatory driers in which a blast of heated air is discharged as a drying means by an electrically operated air mover or blower, and the present improvement has for its object:

To provide a structural formation and combination of parts involving the enclosing shell or casing, the air blower and the operating motor and controlling switch, whereby the supply of air to the air blower is taken from a point remote from motor and from the controlling switch, in order to avoid contamination of such air with the odor and other offensive properties of the oils used as a lubricant on such mechanisms, all as will hereinafter more fully appear.

In the accompanying drawing:

Fig. 1, is a transverse section on line 1,—1, Fig. 2, of an apparatus embodying the preferred form of this invention.

Fig. 2, is a longitudinal section on line 2,—2, Fig. 1.

Like reference numerals indicate like parts in both views.

In the preferred form of the invention shown in the drawing, the enclosing housing 1 of the drier is of an open bottom rectangular shell form, provided on its top wall with an outlet nozzle 2, preferably arranged in an oblique manner as shown in Fig. 1. The open bottom of the housing 1, is adapted to enclose a base plate 3, fixedly secured to said housing with such base plate forming a support for the hereinafter described air mover or blower, electric motor for such air mover and the switch mechanism controlling such motor.

The shell or casing 5 of the air mover or blower above referred to, is arranged centrally within the enclosing housing 1, of the apparatus, with the electric motor 6, arranged at one side of the casing 5 and the controlling switch 11 for said motor arranged at the opposite side of said casing 5, as illustrated in Fig. 2.

As in a former application, Serial Number 114,058, filed June 7, 1926, a heating element 7, of the electrical resistance type is

arranged in the outlet neck of the shell or casing 5 of the air mover or blower, said outlet neck having communication with the heretofore described outlet nozzle 2, of the main housing 1.

In the construction shown, the fan wheel 8 of the air mover or blower is revolvably mounted in the casing 5, and is preferably of the twin section type, having intake openings central of its respective side walls, said side walls having the usual central orifices 5' in alignment with the aforesaid intake openings of the fan wheel 8.

The material feature of the present improvement in connection with air mover construction above described involves the provision on each side wall of the casing 5, of a closed supply trunk 9, having communication with an opening 5' of the casing 5, the inlet opening 10 of each trunk 9, and preferably at the lower end of the same, extending down through the base plate 3. With such arrangement pure air from beneath the main housing 1, of the apparatus, remote and free from contamination of lubricant odors, etc. of the operating mechanism of the apparatus, is supplied to the air mover or blower and is in turn discharged in a heated condition through the outlet nozzle 2 for lavatory drying uses.

The controlling switch mechanism 11, shown in the drawing for controlling the supply of electricity to the electric motor 6, and heating element 7, forms the subject matter of a prior application for patent, Serial Number 236,490, filed November 29, 1927, and of which the present application is a division.

I claim as my invention:

In an electrically operated drier of the type described, the combination of a main enclosing housing having an open bottom, a base plate fitting the open bottom of said housing, an air mover having its enclosing casing mounted at the mid-length of said base plate and having an outlet extending through a wall of the main housing, a heating element arranged in said air mover casing, a motor for said air mover arranged at one side of its enclosing casing, a switch

mechanism controlling said motor and arranged at the other side of the air mover casing, and a closed inlet trunk arranged between the motor and the air mover casing with a wall of said casing having a bearing orifice for the shaft of said motor, said closed inlet trunk being carried by the aforesaid

base plate and opening at one end through said base plate with its other end having communication with the interior of the air mover casing.

In testimony whereof I hereunto affix my signature.

GEORGE A. BURGESS.
